UNITED STATES PATENT OFFICE.

JEAN PERNET, OF ZURICH, SWITZERLAND.

DIATHERMIC APPARATUS.

Application filed August 23, 1926, Serial No. 131,056, and in Switzerland September 30, 1925.

The subject matter of the present invention is a diathermic apparatus for treating the scrotum, particularly in case of epididymitis gonorrhoeica by means of an electrode arranged in a non-conductor.

A successful treatment of this disease commonly termed inflammation of the testicles by means of diathermy could not be carried out heretofore as the necessary apparatus for applying high frequency current to the afflicted parts were not available. The increased sensibility against pain and the peculiar shape of the organ in question wholly excluded the application under pressure of any contact means, as otherwise on account of a local concentration of the current at the places in which the pressure is applied, or on the wrinkled skin, or on the edges of the electrodes or also on account of an unsuitable and non-uniform distribution of the lines of current between the faces of the electrodes so much harm might be done to the organs that the remedial success is much hindered. From similar reasons the application of the so-called apron-electrodes which otherwise have extensively been used in diathermic treatment, i. e. of electrodes in the form of thin pliable metal foils, which are placed on the parts to be treated and pressed against the latter is not possible. In applying such electrodes to the scrotum faulty contact and the formation of sparks occurred owing to the changing shape and the movability of the scrotum.

The application of a stronger pressure for obviating the last mentioned drawback is not possible on account of the danger of causing pains and of mechanically injuring the afflicted organ. These means are placed in a more or less labil state on the scrotum and a steady application, which is the principal requirement, cannot be attained as displacement of the scrotum and of the electrodes occurred frequently during the comparatively long duration of the treatment and particularly when the patient moves.

Moreover with the known apparatus neither the edge effect can be overcome with safety nor can the electrode be so positioned that it is completely stable during the use and that the counter-electrode can be placed in the right position relatively to the electrode (in order to avoid a non-uniform distribution of the stream lines).

In order to avoid the edge effect caused by the edges of the electrodes being pressed into

the organ by the exerted mechanical pressure, apparatus has been proposed with which the electrode is arranged in a non-conductor surrounding the edges of the electrode and being flush with the surface of the electrode. However these proposals have only been made for electrodes consisting of flat plates which cannot be used for treating the scrotum. Further with such electrodes only the edge effect caused by a mechanical pressure can be remedied but not the edge effect caused by the accumulation of stream lines owing to a faulty relative position of the electrode and of the counter-electrode when the electrodes get displaced during the treatment.

These drawbacks are overcome by the apparatus according to the present invention in which the non-conductor is a carrier provided with straps for being fixed to the body of the patient and having a cavity shaped to correspond to the afflicted scrotum, the electrode being arranged in the surface confining the cavity and shaped according to this surface.

An apparatus of this type may be successfully applied and without any pressure being exerted and pain or any other inconvenience being caused to the patient, as the scrotum fits into the cavity without folds being formed in its skin so that the above mentioned disadvantages and injuries are completely overcome.

A constructional example of the subject matter of the present invention is illustrated on the accompanying drawings, in which:

Fig. 1 is a side-view of the apparatus.

Fig. 2 is a vertical section along line II-II in Fig. 3.

Fig. 3 is a horizontal section along line III-III in Fig. 1 and

Fig. 4 shows on a larger scale a cross-section of the electrode.

The apparatus comprises as a non-conductor a peculiarly shaped carrier body 1 made of a solid mass having the required qualities with regard to resisting heat and which can easily be disinfected to respond to the requirements of asepsis. A suitable material is for instance gypsum. This carrier body 1 is arched and the inner surface *a* of it is shaped according to the form of the scrotum taking into account an average enlargement of the swollen afflicted organ and forms a cavity, which on being applied contacts with the scrotum from the left hand

side; the apparatus illustrated is thus intended for a left hand application. One of the lateral faces *b* is a plane surface and is approximately parallel to the centre line of the scrotum and at a distance of approximately 1 cm. from that line when the apparatus is in position. The other lateral face *c* is bulged in and is intended to bear on the upper part of the thigh and is shaped to the outline of the latter. At its lower end the inner face *a* joins to a face *d* which is partly of a convex and partly of a concave shape and is intended to bear partly against the perineum and partly against the body part of the patient between the upper part of the thigh and the scrotum. Finally the carrier body is provided with an outer surface *e* extending approximately parallel to the inner face *a* and having its end parts designed with regard to strength, the outer surface *e* does not rest on the body of the patient.

In the middle portion of the inner surface *a* an oval-shaped, flat, metallic electrode 2 is provided which is exactly parallel to the inner surface *a* and fits thus the part of the scrotum bearing against it. The size and the position of this electrode is such that it approximately bears against the epididymis and covers the latter completely, i. e. it is somewhat larger than is absolutely necessary in order to come into contact with the region of epididymis with different individuals, as the current has to pass mainly through the epididymis. As is shown in Fig. 4 the edges of the electrode are chamfered so that the surface of the electrode passes gradually into the surface *a* of the carrier. Thereby results a uniform distribution of pressure over the whole surface with which the apparatus is in contact with the scrotum so that the formation of folds is completely excluded. In the middle of the electrode 2 a connecting screw bolt 3 is provided serving for fixing the electrode to the carrier and for being connected to the current supply. At the upper and lower ends of the carrier metallic pins 4 are provided to which the ends of a strap 5 passing around the body of the patient, of a strap 6 passing around the upper part of the thigh and of an elastic strap 7 passing around the scrotum are fixed, whereby the electrode and the scrotum are nondisplaceably held in their relative positions.

As has been mentioned above the apparatus illustrated serves for a left hand application; an apparatus for right hand application is exactly symmetrical. With a two sided affliction both apparatus may be simultaneously applied whereby between the lateral faces *b* a gap is present which is sufficient to adapt the two apparatus to the scrotum. In this case one of electrodes may serve as counter-electrode to the other,

whilst with a one-sided application one of the usual apron-electrodes, placed for instance on the lumbar region, is used as counter-electrode.

In order to be able to treat all the different individuals two or three sizes of the apparatus are sufficient.

The electrode 2 may also be placed in any other position in the carrier when it is desired to treat other organs besides the epididymis in the scrotum for instance the electrode may be placed at the edge of the inner surface *a*. Further the electrode may be provided with an extension following the spermatic cord.

Instead of gypsum any other non-conducting, more or less solid or elastic material, for instance vulcanized rubber, vulcanized fibre and the like may be utilized.

Obviously instead of being placed on the inner surface of the carrier the electrode may be recessed in that surface, whereby the surface of the electrode may be flush with the inner surface of the carrier or may be lower than the latter.

The above described apparatus has been successfully utilized in practice and it permits not only an experienced specialist but also a less skilled medical man to make use of a non-dangerous diathermic treatment in curing afflictions of the scrotum.

I claim:

1. An apparatus of the type described, comprising a non-conductor having a cavity the shape of which corresponds to the shape of the afflicted one half of the scrotum with which it has to contact while supporting the latter, an electrode arranged in said cavity and shaped to form with the walls of said cavity, a smooth surface, and means adapted to detachably fix the non-conductor to the body of the patient.

2. An apparatus of the type described, comprising a non-conductor having a cavity the shape of which corresponds to the shape of the afflicted one half of the scrotum with which it has to contact while supporting the latter, an electrode recessed in said cavity and shaped to form with the walls of said cavity a smooth surface the surface of the electrode being flush with the surface of the cavity, and means adapted to detachably fix the non-conductor to the body of the patient.

3. An apparatus of the type described, comprising a non-conductor having a cavity the shape of which corresponds to the shape of the afflicted one half of the scrotum with which it has to contact, while supporting the latter, an oval plate electrode arranged in said cavity and shaped to form with the walls of said cavity a smooth surface, and means adapted to detachably fix the non-conductor to the body of the patient.

4. An apparatus of the type described, comprising a carrier made of a non-con-

ductive material and having a cavity shaped to correspond to the shape of the afflicted scrotum with which it has to contact and being provided with a plane lateral face and a curved lateral face for bearing against the upper part of the thigh, the lower part of the cavity joining to a face shaped to contact with the perineum and with the body part between the upper part 10 of the thigh and the scrotum, a plate electrode arranged in said cavity and shaped to form with the walls of said cavity a smooth surface, and means adapted to detachably fix said carrier to the body of the 15 patient.

5. An apparatus of the type described, comprising a carrier made of a non-conductive material and having a cavity shaped to correspond to the shape of the afflicted 20 scrotum with which it has to contact and being provided with a plane lateral face and a curved lateral face for bearing against the upper part of the thigh, the lower part of the cavity joining to a face

shaped to contact with the perineum and 25 with the body part between the upper part of the thigh and the scrotum, a plate electrode arranged in said cavity and shaped to form with the walls of said cavity a smooth surface, and straps adapted to 30 detachably fix said carrier to the body of the patient.

6. An apparatus of the type described, comprising a carrier made of a non-conductive material and having a cavity shaped 35 to correspond to the shape of the afflicted scrotum with which it has to contact, an oval plate electrode arranged in said cavity and shaped to form with the walls of said cavity a smooth surface, a screw bolt fixed to said plate electrode and serving to connect the latter to said carrier and to connect it to a source of current, and means adapted to detachably fix the non-conductor to the body 40 of the patient.

In testimony whereof, I have signed by 45 name to this specification.

JEAN PERNET.
